United States Patent Office.

HARVEY D. HARADEN, OF HARTFORD, VERMONT.

Letters Patent No. 77,037, dated April 21, 1868.

IMPROVED CLOTHES-PIN.

The Schedule referred to in these Letters Patent and making part of the same.

TO ALL PERSONS TO WHOM THESE PRESENTS MAY COME:

Be it known that I, HARVEY D. HARADEN, of Hartford, in the county of Windsor, and State of Vermont, have invented an Improved Clothes-Pin or Spring-Clip; and I do hereby declare the same to be fully described in the following specification and represented in the accompanying drawings, of which—

Figure 1 is a side elevation, and

Figure 2 a top view of it.

Figure 3 is a side view of the block, showing the arrangement of the saw-kerfs made in it for converting it into a clothes-pin.

In making the said clothes-pin, I take a piece of wood, A, in the form of a quadrilateral prism, and first bore a hole, b, through it laterally, near one end of it, and nearer to the lower than to the upper edge of it. Next, by means of a saw, I make a kerf or slit lengthwise in the piece of wood, the said kerf being arranged in manner as represented at a, which shows it as going diametrically through the hole b, and extending about two-thirds the distance through the piece, from that end of it which is next to the hole b. Next I make two other saw-kerfs in the piece from its other end, and at an acute angle with each other, in manner as shown at e and f in fig. 3, whereby I remove from the piece a wedge, g, and form it with an open space, as shown at c in fig. 1. The portion h, comprehended between the slits a and f and their inner ends, is thus made to operate as a hinge and spring-connection of two jay-levers, i k, made by sawing into the piece in manner as described.

I prefer, however, to place within the space c a metallic spring, d, which I insert in the piece A at the vertex of the opening, c, the spring being bent so as to bear against the tails of both levers.

In this way I form, from a single piece of wood, a spring-clip or clothes-pin.

I do not claim a furcated clothes-pin made of a single piece of wood, split or sawed into from one end only; that is to say, so to make it in the form as represented in fig. 4 of the accompanying drawings.

Nor do I claim a clothes-pin as represented in the United States Patent, No. 14,262.

In my invention the jaws i k are formed by the single slit or saw-kerf a, of an equal width throughout, and I make but one spring-opening, c, and I employ a separate spring, d, which I arrange therein in manner as represented.

I therefore claim my improved clothes-pin, consisting not only of the piece of wood A, having the slit a, the angular opening c, and the hole b, formed and arranged in it as described, but of the spring d arranged in the said slit, the whole being substantially as described.
